PAGE 2

Fig. 2

FIG. 1 is a front perspective view of the sewing machine;

FIG. 2 is a rear perspective view of the sewing machine; and

FIG. 3 is a top plan view of the sewing machine.

The dominant features of the design reside in the shape and inclination of the standard and in the shape of the cross-arm and the handwheel projection in relation to the standard and the handwheel.

I claim:

The ornamental design for a sewing machine or similar article, as shown and described.
